1

This invention relates to indicating systems for use in determining the conduct of a projectile in a gun barrel. More particularly, the invention has reference to a novel system of this character in which an electrical potential is generated in the projectile when it is fired in the gun, the potential being utilized to operate an electrical indicating device. The new system is of simple form and may be operated readily to provide accurate measurements. The potential for operating the indicating device is generated in a projectile of novel construction which also forms part of the invention.

One object of the invention resides in the provision of a novel system for indicating phenomena associated with the movement of a projectile through a gun barrel, in which the indicator is operated by an electrical potential generated in the projectile by the action of a force resulting from firing the projectile, for example, a force due to the pressure from the explosion of the firing charge or to the set back of a member in the projectile. The new system comprises means in the projectile for generating an electrical potential, the generating means being preferably in the form of a piezo-electric crystal which is compressed by the above-mentioned force. An electrical-indicating device, which may be located remotely from the gun, is operated by the potential thus generated in the projectile. In the preferred construction, the potential is impressed across the indicating device by conducting means including a wire connected to one side of the generating means and extending from the nose of the projectile along the bore of the gun through the muzzle, and insulated from the gun, to one side of the indicating device, the other side of the device being connected through the gun and the projectile body to the other side of the generating means. The wire in the gun bore may be coiled and the nose of the projectile provided with an insulated collector unit for receiving the wire as the projectile moves through the bore.

Another object of the invention is to provide a novel projectile having means which, when the projectile is fired, generates an electrical potential for use in measuring a force resulting from firing the projectile. A projectile made in accordance with the invention comprises an electrical potential generating means, such as a piezo-electric crystal, in the projectile body, and means for subjecting the crystal to a compression commensurate with a force to be measured. The compressing means may include a member movable relative to the projectile body for exerting

2

a force of set back against the crystal, or a piston actuated by the gaseous pressure due to explosion of the firing charge. Preferably, the generating means has an electrical connection extending from one side through the body and insulated from the body, the other side of the generating means being electrically connected to the projectile body, whereby one side of an indicating device outside the gun may be connected through the gun bore or chamber to the insulated connection, and the other side of the gun which provides a conducting path to the projectile body.

The new system is easy and inexpensive to operate and provides an accurate and positive indication of phenomena associated with movement of the projectile along the gun barrel when the gun is fired. Since the means for generating the indicating pulse is located in the projectile itself, the system may be used with a gun of ordinary form and it is unnecessary to employ any special attachment on the gun. The pulse generating means in the projectile is of compact construction and may be used in a projectile of any desired form.

These and other objects of the invention may be better understood by reference to the following detailed description and the accompanying drawings, in which

Fig. 1 is a diagrammatic view of one form of the new indicating system;

Fig. 2 is an enlarged perspective view of the nose portion of the projectile shown in Fig. 1;

Fig. 3 is an enlarged axial sectional view of the upper portion of the part of the projectile shown in Fig. 2;

Fig. 4 is a perspective view of the wire collector unit shown in Figs. 1, 2 and 3;

Fig. 5 is a similar view of the container for the electricity generating means shown in Fig. 3;

Fig. 6 is an exploded view of the electricity generating means;

Fig. 7 is an axial sectional view of part of a modified form of the new projectile, showing the electricity generating means, the wire collector unit and the electrical connections;

Figs. 8, 9 and 10 are perspective views of parts of the projectile shown in Fig. 7; and

Figs. 11 and 12 are axial sectional views of two other forms of the projectile.

The indicating system of the invention comprises a projectile body preferably including a casing 20, a rotating band 21 near the tail end of the casing and a nose 22 threaded into the casing. The projectile is loaded in a gun 23 having a bore 23a provided with the usual rifling

(not shown), the main portion of the projectile being disposed in the bore with the rotating band 21 in the chamber to the rear of the bore so that the band becomes engraved by the rifling when the projectile is fired. The projectile, as shown, is of the fixed ammunition type and is held at its tail end in the gun chamber in the usual cartridge case 24 containing the firing charge, although it will be understood that the firing charge may be packed in bags in the gun chamber and the case 24 eliminated. At the rear of the gun is the usual breech mechanism designated generally at 25.

In the nose portion 22 of the projectile is a generating unit 26 for generating an electrical potential through the action of a force resulting from firing the projectile. One side of the generator is insulated from the projectile and connected to a conductor 27, which is preferably a bare copper wire extending in coils from the nose portion of the projectile along the bore 23a and out the muzzle of the gun, the wire being held loosely at the muzzle by suitable means (not shown) so that there is no electrical contact between the wire and the gun. The end of the wire remote from the gun is connected to one side of an indicating apparatus 28, the other side of which is connected through a wire 29 to the gun, whereby a closed circuit is formed from one side of the generator 26, through the wire 27, indicating apparatus 28, wire 29, gun 23, and projectile body 20 to the other side of the generator.

In operation, when the gun is fired, the electrical potential built up by the generator 26 in the projectile is impressed across the indicating apparatus 28 which provides a measure of the potential so that the magnitude of the force utilized in generating the potential may be determined. From the values thus indicated by apparatus 28, phenomena incident to the conduct of the projectile as it moves through the gun barrel may be determined, such as acceleration, set back, etc. As the projectile moves along the bore 23a, the wire 27 is collected in coils in the nose of the projectile in a suitable insulated collector unit, which will be described in detail presently, so as to prevent contact between the wire and the gun with a resulting short-circuit of the indicating apparatus. The apparatus 28 may include an oscillograph operated by the electric charge from the projectile, and a camera for recording the operation of the oscillograph. It will be understood that instead of including the indicating apparatus in a closed circuit, as shown, the said apparatus may take the form of a receiving set responsive to the electric charge in the wire 27, whereby the connection 29 to the gun may be eliminated.

The projectile shown in Figs. 1 to 6 inclusive comprises an inner cup 31, which may be made of steel, located in a recess in the nose 22, the cup having its open end facing forward, and being held in the recess in any suitable manner, as by means of a press fit. Intermediate its ends, the cup is formed with an external shoulder 32 engaging the end of the nose 22. Within the cup 31 is an inverted inner cup 33 made of insulating material, such as Lucite. At the open end of the inner cup 33 is a metal base plate 34 connected to the inner cup by screws 35. The forward end of the plate 34, which is reduced, fits closely in the cup 33 and engages a copper disc 36 disposed between the said plate and electricity generating means comprising a piezo-electric crystal 37 surrounded by an insulating retaining washer 38. In front of the crystal 37 is another copper disc

39 disposed between the crystal and a metal block 40 fitted closely in the cup 33 and movable relative thereto.

The interior of the outer cup 31 is enlarged at its open end to provide a shoulder 42, and seated in the enlargement on the shoulder is a collector unit comprising an insulating cup 43 held in position by a set screw 44 with the open end of the cup 43 facing forward. A cup-shaped collector electrode 45 is held in the cup 43 with the open end of the electrode facing forward, the electrode being provided with an external shoulder 46 engaging the nose end of the cup 43. The inner wall of the electrode cup converges from the front of the cup to a plane intermediate its ends, as shown at 45a, and then diverges outwardly to the bottom of the cup, as shown at 45b. If desired, the collecting electrode 45 may be a simple cylindrical cup.

The collector or take-up electrode 45 is electrically connected to the block 40 by a connection comprising a plug 48 held in the insulating cup 43 and having a stem 49 in the electrode 45. The plug 48 has a spring contact 50 received in a socket 51 in the closed end of the insulating cup 33, the latter being provided with a recess 52 for receiving the socket. If desired, the insulating cups 33 and 43 may be cast around the socket 51 and plug 48, respectively. The socket 51 is connected to the block 40 by a conductor 53 extending through a passage in the cup 33. A screw 54 driven into the bottom of the collector electrode 45 provides a terminal for connection to the coiled wire 27 leading to the indicator 28.

When the gun is fired, the projectile accelerates in the bore 23a and causes the block 40 to exert a force of setback against the crystal 37. As a result, an electrical potential difference is generated by the crystal and is impressed across the indicator 28 from the block 40 through conductor 53, socket 51, plug 48, electrode 45, and wire 27, and from the base plate 34 through the outer cup 31, the projectile body 20-22, gun 23, and wire 29. Accordingly, the indicator provides a measure of the voltage generated by the crystal 37, from which the force of setback of the block 40 may be computed. Since the mass of the block is known, the acceleration of the projectile as it moves along the gun bore may be determined. The coiled wire 27, as the projectile moves along the bore, is collected in the electrode 45, the conical surface 45a serving to direct the coils into the bottom portion 45b of the electrode where they are held by the restricted portion of the electrode. The collector unit 43-45 may be readily removed from the projectile by loosening the set screw 44, the plug and socket 48-51 providing a releasable electrical connection between the collector unit and the block 40. When the parts are assembled, the collector unit 43-45 holds the inner cup 33 firmly in the outer cup 31, and the electricity generating means, the block 40 and the plate 34 are held securely in the inner cup.

The projectile shown in Fig. 7 is generally similar to that shown in Fig. 3 but includes means for counteracting the effect on the piezo-electric crystal of extraneous influences, such as vibration of the case 58 or the force of setback on the parts. In the projectile shown in Fig. 7, the nose portion 22a is provided with a recess for receiving a metal cup 56, which is held in the recess with the open end of the cup facing forward. Intermediate its ends, the cup is provided with an external shoulder 57 engaging the end of the nose 22a. Within the cup 56 is a metal case 58

of cylindrical form made of aluminum or other metal. The ends of the case are threaded to receive metal plugs 59 and 59a respectively, the plugs having reduced portions 60 and 60a, respectively, extending into the interior of the case 58. The plugs are adjustable in the case, and, to this end, may be provided with openings 61 for receiving a wrench. An insulating sleeve 62, which may be made of Lucite, is disposed in the case 58 between the reduced portions 60 and 60a of the plugs, the sleeve containing a metal block 63 held closely in the sleeve but movable relative thereto. At the ends of the block are copper discs 64 which engage piezo-electric crystals 65 and 66 clamped between the discs 64 and similar discs 64a on the reduced plug portions 60 and 60a, respectively.

The interior of the cup 56 is enlarged at its open end to receive a collector unit 43a—45a similar to the unit 43—45 in Fig. 3, the unit being seated on a shoulder 42a in the cup 56 and held in position by a set screw 44a. The collector electrode 45a is electrically connected to the block 63 through a connection comprising a plug 48a in the insulating cup 43a, the plug having a stem 49a extending into the electrode. A spring contact 50a of the plug is received in a socket 51a in an insulating plug 67 disposed in a recess in the case 58 at one side of the sleeve 62. A conductor 68 extends from the socket 51a through a passage in plug 67 to an opening 69 extending transversely through the plug and the case to the sleeve 62. An insulating bushing 70 in the opening 69 has a recess in its outer end portion in which the conductor 68 is connected to another conductor 71 extending inwardly through the bushing and through an aligned opening in sleeve 62 to the block 63. In its inner end portion, the bushing 70 has a conical recess 72 which flares toward the block 63 to permit movement of the block relative to the bushing without injuring the electrical connection to the block. A screw 54a in the collector electrode 45a serves as a terminal for connection to the wire 21 leading to the indicating apparatus.

In the use of the projectile, the plugs 59—59a are tightened in the case 58 so as to force the crystals 65 and 66 against block 63 and subject them to an initial compression. The crystals are arranged in opposing relationship so that the potential difference generated by crystal 65 tends to counteract that generated in crystal 66, and to this end the positive side of one of the crystals and the negative side of the other crystal are disposed adjacent the block 63. The plugs 59 and 59a may be adjusted in the case by loosening set screw 44a, removing the collector unit 43a—45a, raising the case 58 from cup 56, and applying a wrench to the plugs. When the plugs 59—59a have been adjusted, they may be locked in their adjusted positions by set screws 73 in the case 58, after which the parts are assembled as shown.

When the projectile is fired, the force of setback of block 63 causes the block to increase the pressure on crystal 66 and decrease the pressure on crystal 65, whereby the block is charged more highly with a charge corresponding to that on the adjacent side of crystal 66, while the projectile is charged more highly with an opposite charge through the plugs 59—59a, case 58 and cup 56. It will be observed that the charge placed on block 63 by a change in the pressure on crystal 66 due to either a positive or a negative force of setback is of the same sign (i. e. positive for a positive setback and negative for a negative

setback) as that placed on block 63 by the resulting opposite change in the pressure on the other crystal 65. The potential thus generated is impressed across the indicating apparatus 28 from the projectile through the gun 23 and wire 29, and from the block 63 through conductors 71 and 68, plug and socket 48a, 51a, electrode 45a and wire 27.

When the projectile is fired, any vibrations or other forces therein tending to affect the potentials generated in crystal 66 by the setback force of block 63 also produce in the crystal 65 an equal change in potential which opposes the change in crystal 66. Accordingly, these vibrations or other forces have no effect on the ultimate potential difference generated between the block 63 and the projectile. Also, by reason of the opposing crystals 65—66, the generator compensates for changes in prestressing thereof due to adjustment of the plugs 59—59a. In the event that the case 58 is compressed by the force of setback, the resulting increase in pressure on crystal 66 is counteracted by a corresponding increase in the pressure on crystal 65, so that there is no change in the indicated voltage. Since the crystals 65 and 66 are arranged to produce opposite charges on the block 63 when they are compressed, a positive setback generates a positive charge on the block relative to the projectile body 22a, and the gun 23, and a negative setback generates a negative charge on the block with respect to the projectile body 22a and the gun 23. Accordingly, both positive and negative setbacks may be measured. The case 58 is preferably made of aluminum so as to increase its resonant frequency, whereby its vibrations will have substantially no effect on the generated potentials.

The projectiles shown in Figs. 11 and 12 are similar in principle to those illustrated in Figs. 40 3 and 7 but are suitable for use in measuring the pressure to which the tail end of the projectile is subjected by the explosion of the firing charge in the gun. The projectile shown in Fig. 11 comprises a body including a case 22b having the usual rotating band 21b and nose 22b. At its tail end, the projectile is held in a cartridge case 24b containing the usual firing charge 75. Mounted in a recess in the tail end of the projectile is a cup-shaped cylinder 76 made of insulating material, such as Lucite, the open end of the cylinder facing to the rear. A metal plunger 77 fits closely in the cylinder and is movable therein. Secured to the open end of cylinder 76, as by means of screws 78, is a retaining plate 79 for the plunger. The plate 79 also serves as a baffle and, to this end, is provided with a plurality of lateral ports 80 communicating with a central longitudinal passage 81 leading to the plunger. Between the inner end of the plunger and the inner end of cylinder 76 is an electricity generating means comprising a piezo-electric crystal 82, the generating means being similar to that shown in Fig. 3. One side of the crystal 82 is grounded to the projectile body, as shown at 82a, and the other side is connected through a conductor 83a on the plunger to a terminal 83 held in the wall of cylinder 76. The terminal projects from cylinder 76 into a recess 84 in the projectile where it is connected to a wire 85 extending through a passage 84a in the projectile into the main chamber of the casing 23b. The wire 85 is insulated from the projectile and is connected near the nose thereof to the terminal 54b of a collector unit 43b—45b similar to that shown in Figs. 3 and 7.

Upon firing the projectile in a gun, the pressure resulting from the explosion of the firing charge is communicated through the ports 80 in the baffle to plunger 91 and forces the plunger against crystal 82 so as to generate an electrical potential difference between the opposite faces of the crystal. The electric charge built up by the crystal as a result of the explosion of the firing charge is impressed across the indicator through wire 83a, terminal 83, wire 85, terminal 54b and wire 27b, and through the projectile body 20b, gun 23 and wire 29.

In the projectile shown in Fig. 12, the casing 20c carries a rotating band 21c and a nose portion 22c, and the tail end of the casing is held in a cartridge case 24c. In its tail end, the projectile has a recess for receiving a metal case 87 which may be held in the recess in any suitable manner. Outside the recess, the case is formed with an external shoulder 86a engaging the rear end of the projectile. A cylinder 88 secured in the tail end of the case 87 is provided with an externally threaded boss 88a on which a baffle element 89 is screwed, the baffle element having ports 89a for admitting pressure fluid resulting from explosion of the firing charge in the cartridge case. Slidable in the case 87 in front of the cylinder 88 is a metal block 90 having at its rear end a plunger 91 in the cylinder, the plunger being preferably connected to the block by releasable means, such as a threaded stud 92. An obturator 91a, which may be made of Duprene, or the like, is disposed on the free end of the plunger. Seated in the front end of block 90 is the dome portion of a hemispherical element 93, the base of which engages a piezo-electric crystal which, as shown, is made up of a plurality of quartz discs 94. The discs 94 are retained in an insulating sleeve 95 within the case 87 and are interposed between the hemispherical element and a metal follower 96 in the sleeve. The front end of sleeve 95 is closed by an insulating disc 97 engaging the adjacent face of the follower, and the disc 97 is clamped against the sleeve and the follower by a metal plug 98 threaded into the front end of case 87. The plug 98 is provided with a central opening for receiving an insulating collar 99 through which the shank of a terminal post 100 extends, the rear end of the post being imbedded in the follower 96. At its front end, the post 100 is connected to an insulated wire 85a extending through the chambered interior of the projectile to a terminal screw 54c mounted at the nose of the projectile on an insulated collector unit 43c-45c. The terminal 54c is designed to be connected to one side of the indicator 28 by the coiled wire 27 extending through the bore of the gun, the other side of the indicator being connected through wire 29, gun 23 and the projectile body to the other side of the generator 94.

The operation of the projectile shown in Fig. 12 is generally similar to that of the one shown in Fig. 11. When the projectile is fired, the pressure from the explosion is directed against plunger 91, the baffle 89 preventing solid powder grains from striking the plunger and producing spurious signals. The plunger then compresses the crystals 94 through the block 90 and the hemispherical element 93, which provides uniform loading of the crystals. If desired, thin sheets of annealed copper (not shown) may be placed between adjacent faces of the crystal discs 94 to distribute the load where there are minor irregularities in the surfaces of the crystals. As a result of their compression, the crystals 94 gen-

erate an electrical potential difference, one charge of which is conducted through an insulated conducting path comprising follower 96, post 100, wire 85a, terminal 54c, and wire 27 to one side of the indicator. The opposite charge is conducted from the hemispherical element 93 through case 87, the projectile body, the gun, and wire 29 to the other side of the indicator.

If desired, the cylinder 88 and plunger 91 may be removed and replaced by a cylinder and plunger of different size so as to provide a new ratio between the mass of the moving parts in the projectile and the area of the plunger, to correspond with the new mass to area ratio of a different projectile, whereby measurements for projectiles of several different sizes may be made with the same electricity generating means.

The use of the invention may be more readily understood by reference to the following relations:

According to Newton's law the forces on a projectile of mass M and cross-sectional area A are (1) $Ma = PA = R$, where a is acceleration; P is pressure, and R is bore friction. Also, the force on the plunger 91 is (2) $ma = PB - F$, where m is the mass of the plunger; a is the acceleration of the plunger by confinement in the projectile; P is pressure; B is the area of the plunger, and F is the force of the crystal on the plunger. Solving for the acceleration and equating (1) and (2):

$$\frac{PA}{M} - \frac{R}{M} = \frac{PB}{m} - \frac{F}{m}$$

With the mass to area ratio of the projectile equal to the mass to area ratio of the plunger 91, the terms involving pressure will cancel, leaving

$$\frac{R}{M} = \frac{F}{m} \text{ or (3) } F = \frac{mR}{M}$$

In the foregoing it is assumed that there is no effect of friction on the plunger, which is a reasonable assumption since the plunger is confined and clearances are relatively large. Accordingly, the effect of pressure is eliminated, and only known or readily measurable values are involved.

From measurements made while pushing a rifling band through a forcing cone, it is reasonable to expect a maximum friction force of about 25 tons between the projectile and the gun barrel. In a 3" projectile having a mass 12.8 lbs. and containing a plunger 91 having a mass of 0.2 lb., the force on the piezo-electric crystal according to Equation 3 is

$$F = \frac{0.2}{12.8} \times 25 \times 2 \times 10^3 \\ = 780 \text{ pounds}$$

With four quartz crystals 94 of a Curie constant, K , of 8.5×10^{-12} coulombs, Q , per pound, the maximum signal to expect is

$$4 \times 8.5 \times 10^{-12} \times 780 = 2.65 \times 10^{-8} \text{ Q/lbs.}$$

There are a few obvious sources of error in the new system, but their importance may be determined so that they may be properly evaluated and corrected in the mathematical calculations based on the readings of the indicator. One possible error is mismatching of the mass to area ratio of the plunger and the projectile. This may be corrected by drilling out a portion of the plunger to adjust its mass. If an error still exists, its effect on the calculated results may be counteracted on the basis that the size of the error is PEB , where P is the pressure acting on the plunger 91, B is the area of the plunger, and

E is the assumed percentage error in matching. Another possible source of error is the baffle 89, which may produce a hysteresis effect caused by a retarded action on the plunger of the gas pressure which produces the signal. Since the gas is "piling up" and not flowing straight through the baffle, the error will probably be one due only to the increased length of the path, which error is of the order of microseconds. Another possible error is that caused by loosening of the electricity generating assembly due to the spin of the projectile. To prevent such loosening, the threads on the parts in the assembly may be so arranged that the spin tends to tighten them so as to hold the parts more firmly. The end plate members 97-98 adjacent the crystals 94 are thick enough to prevent any substantial deflection and compression of the crystals under the maximum load imposed by the set back force of the explosive charge in the projectile.

It will be evident that the system of this invention may be used for several different purposes. For example, it may be used for timing parts of fuzes or safety devices in the projectile and for determining the acceleration of the projectile, vibrations of the parts of the projectile or fuze, the pressure on the base of the projectile, the friction between the projectile and the bore of the gun, the leakage of gas past the projectile in the gun, angular acceleration of the projectile, the strains produced in various parts of the projectile or fuze, or the temperature of the rotating band and the bore of the gun while the projectile is moving out of the gun.

We claim:

1. In combination, a gun barrel, a projectile adapted to be fired from the gun barrel, means in the projectile for generating an electrical potential difference upon movement of the projectile through the gun barrel, an electrical indicating device remote from the gun barrel, and conducting means including a conductor extending from the projectile along the bore of the gun barrel and connecting the generating means to the indicating device.

2. In a projectile having a body, an insulating container in the body, a base plate, electrically connected to the body, a member in the container movable relative to the container, a quartz crystal between the movable member and the base plate, said member being movable upon acceleration of the projectile to compress the crystal and cause the crystal to generate an electrical potential difference commensurate with the set back force acting on the member, a collector terminal mounted on the body and insulated therefrom, an electrical connection between said movable member and the terminal and insulated from the body, for taking up said electrical connection during the travel of the projectile while being fired, and means connected to said body and said terminal respectively, for measuring said potential difference.

3. In combination, a gun barrel, a projectile adapted to be fired from the gun barrel having a body, means in the projectile body for generating an electrical potential difference upon movement of the projectile through the gun barrel, an electrical connection between said body and one side of the generating means, conducting means connected to the other side of the generating means and insulated from the body, said conducting means extending along the interior of the gun and projecting therefrom, a container carried by the projectile for taking up and stor-

ing said conducting means, and an indicator electrically connected to the gun and to said conducting means and outside the trajectory of the projectile, for providing a measure of said potential difference.

4. In combination, a gun barrel, a projectile adapted to be fired from the gun barrel having a body, means in the projectile body for generating an electrical potential difference upon movement of the projectile through the gun barrel, an electrical connection between said body and one side of the generating means, a collector unit at the nose of the projectile and insulated from the body, a conductor extending from said unit through the bore of the gun, said unit including a container for taking up and storing said conductor, an electrical connection between the other side of the generating means and the conductor and insulated from said body, and an indicator electrically connected to the gun and to said conductor for providing a measure of said potential difference, said indicator being located outside the trajectory of the projectile.

5. A projectile comprising a body, a hollow collector unit secured to the body at the nose of the projectile and insulated from the body, a terminal in the collector unit, piezo-electric means in the body for generating an electrical potential difference on firing of the projectile, an electrical connection between one side of the generating means and the terminal and insulated from the body, and an electrical connection between the other side of the generating means and the body.

6. In combination, a gun barrel, a projectile adapted to be fired from the gun barrel, means in the projectile for generating an electrical potential difference upon movement of the projectile through the gun barrel, an electrical indicating device remote from the gun barrel, conducting means including a coiled conductor extending from the projectile along the bore of the gun barrel for impressing said potential difference across the indicating means, and a collector unit at the nose of the projectile for receiving said conductor as the projectile moves along the gun barrel.

7. A projectile comprising a body, a conducting member in the body movable relative thereto on acceleration of the projectile, a piezo-electric quartz crystal at each end of said member, a conducting element engaging each crystal on the face remote from said member, the crystals being normally stressed between said member and the conducting elements, said crystals, conducting member and conducting elements forming a means for generating an electrical potential difference of increasing magnitude as the force of set back of said member increases, an electrical connection between the body and one side of said generating means, and an electrical connection extending from the other side of said generating means to the outside of the body and insulated from the body.

8. A projectile comprising a body having a recess in its nose end, a generally cup-shaped insulating container disposed in the recess with the open end of the container facing the tail end of the projectile, a metal block in the container adjacent the base thereof, a piezo-electric crystal in the container adjacent the tail end of the block, a plate adjacent the tail face of the crystal and electrically connected to the body, a generally cup-shaped collector unit secured to the body in front of the container with the open end of the unit at the nose of the projectile, said unit being insulated from the body, a conducting element in

the collector unit, an electrical connection extending from said block through the base of the container to the conducting element, and an indicator connected to said body and to said conducting element.

9. A projectile comprising a body, means in the body for generating an electrical potential difference on firing the projectile, an electrical connection between the body and one side of the generating means, a generally cup-shaped collector unit disposed at the nose of the projectile with the open end of the unit facing forward, releasable means for securing said unit to the body, said unit being insulated from the body, a releasable electrical connection extending from the other side of said generating means into the collector unit and including plug and socket members, means for insulating said last connection from the body, and an indicator connected to said body and to said electrical connection respectively, to measure said potential difference.

10. A projectile comprising a body having a recess in the nose end, a generally tubular insulating container in the recess extending lengthwise of the body, a metal block in the container, a piezo-electric crystal in the container adjacent each end of the block, a conducting member adjacent each crystal normally pressing the crystal against the block and electrically connected to the body, conducting means extending from the block intermediate the ends thereof through the container to the outside of the body, means for insulating said conducting means from the body, a generally cup-shaped collector unit disposed at the nose of the projectile with the open end of the unit facing forward, said unit being insulated from the body, a conducting element in the collector unit, electrically connected to said conducting means, and an indicator connected to said body and to said conducting element.

11. A projectile comprising a body having a recess in the nose end, a generally tubular insulating container in the recess extending lengthwise of the body, a metal block in the container, a piezo-electric crystal in the container adjacent each end of the block, a conducting member threaded in the body adjacent each crystal for pressing the crystal against the block and electrically connected to the body, the conducting member being adjustable to vary the compression of the crystals, conducting means extending from the block intermediate the ends thereof through the container to the outside of the body, means for insulating said conducting means from the body, a generally cup-shaped collector unit disposed at the nose of the projectile with the open end of the unit facing forward, said unit being insulated from the body, a conducting element in the collector unit, electrically connected to said conducting means, and an indicator connected to said body and to said conducting element.

12. A projectile comprising a body having a recess in the nose end, a generally tubular insulating container in the recess extending lengthwise of the body, a metal block in the container, a piezo-electric crystal in the container adjacent each end of the block, a conducting member adjacent each crystal normally pressing the crystal against the block and electrically connected to the body, an insulating plug in the body adjacent the container, conducting means extending from the block intermediate its ends through the side wall of the container and through said plug to the outside of the body, a generally cup-shaped collector unit disposed at the nose of the projec-

tile with the open end of the unit facing forward, said unit being insulated from the body, a conducting element in the collector unit, electrically connected to said conducting means, and an indicator connected to said body and to said conducting element.

13. A projectile comprising a body having a recess in its tail end, a cylinder of insulating material in the recess, a plunger in the cylinder, a piezo-electric crystal in the cylinder adjacent the inner end of the plunger, the plunger being operable by fluid pressure against the tail end of the projectile to compress the crystal and cause it to generate an electrical potential difference, and an electrical connection extending from the plunger through the body to the outside of the projectile for conducting a charge from the crystal to the nose, said connection being insulated from the body.

14. A projectile comprising a body having a cylinder in its tail end, a plunger in the cylinder, a piezo-electric crystal in the body adjacent the inner end of the plunger, the plunger being operable by fluid pressure against the tail end of the projectile to compress the crystal and cause it to generate an electrical potential difference, one side of the crystal being electrically connected through the plunger and cylinder to the body, an electrical connection extending from the opposite side of the crystal through the body to the outside of the projectile, and means for insulating the crystal and said connection from the body.

15. A projectile comprising a body having a cylinder in its tail end, a plunger in the cylinder, a hemispherical element having its dome portion seated in the inner end of the plunger, a piezo-electric crystal in the cylinder adjacent the base of said element, the plunger being operable by fluid pressure against the tail end of the projectile to compress the crystal and cause it to generate an electrical potential difference, an electrical connection extending from one side of the crystal through the body to the outside of the projectile and electrically insulated from the body, a generally cup-shaped collector unit disposed at the nose of the projectile with the open end of the unit facing forward, said unit being insulated from the body, a conducting element in the collector unit, electrically connected to said electrical connection, and an indicator connected to said body and to said conducting element.

16. A projectile comprising a body having a cylinder in its tail end, a plunger in the cylinder, a piezo-electric crystal in the cylinder adjacent the inner end of the plunger, baffle means on the projectile for directing fluid pressure from the tail end of the projectile against the plunger to cause the plunger to compress the crystal and generate an electrical potential difference, an electrical connection extending from one side of the crystal through the body to the outside of the projectile and electrically insulated from the body, a generally cup-shaped collector unit disposed at the nose of the projectile with the open end of the unit facing forward, said unit being insulated from the body, a conducting element in the collector unit, electrically connected to said electrical connection, and an indicator connected to said body and to said conducting element.

17. In a projectile having a body, an insulating container in said body, means in the container for generating an electrical potential difference in response to firing of said projectile, one side of said generating means being connected electrically to the projectile body, a collector terminal

13

mounted on said body and insulated therefrom, means insulated from the body and electrically connecting said terminal to the other side of said generating means, an electrical conductor also connected to said terminal, said terminal taking up said conductor during the travel of the projectile while being fired, and means for measuring said potential difference, connected to said conductor and to said body respectively.

NICHOLAS M. SMITH, JR. 10
J. ALLEN CROCKER.
